Inventor

Ray H. Anderson

UNITED STATES PATENT OFFICE.

ROY H. ANDERSON, OF ST. JAMES, MINNESOTA.

GARMENT FASTENER.

Application filed October 14, 1920. Serial No. 416,908.

To all whom it may concern:

Be it known that I, ROY H. ANDERSON, a citizen of the United States, residing at St. James, in the county of Watonwan and State of Minnesota, have invented certain new and useful Improvements in a Garment Fastener, of which the following is a specification.

This invention relates to garment fasteners and particularly to a snap fastener for ladies' garments, gloves, et cetera.

The primary object of the invention is to provide a snap fastener which can not be accidentally or casually pulled apart after being connected.

Other objects of the invention will appear upon consideration of the following detail description and accompanying drawings, wherein:—

20 Figure 1 is a perspective view showing the two elements which constitute the connecting members for the fastener,

25 Figure 2 is a longitudinal section through the same,

Referring to the drawing by numerals, a portion of the garment 1 has one of the elements attached thereto and the same consists of a plate 2 secured by fastening members 3 to the garment this being accomplished by thread or any other fastening means according to the size of the fastener and the type of goods to which it is attached. Projecting centrally from the plate 2 is a stud 4 upon which a spherical stop member 5 is mounted.

Attached to the portion of the garment 6 to which the portion 1 is to be attached is the complementary fastening member 7 which consists of a disk 8 secured by the fastening members 9. Near the center of the disk 8 is an opening which has a circular end 10 in communication with a rectangular

slot 11. From the outer terminal of the slot 11 extends a resilient spring 12 formed in any suitable manner but which may be 45 constructed by a pressed out portion of the material from which the plate is made. This member 12 is resilient and terminates in a finger clamp 13.

As illustrated in Fig. 2, the two members 50 are assembled by passing the spherical stop member through the opening 10 so that the stud is lodged in the opening and the spring member 12 forces the member 13 into engagement with the spherical stop member 5. 55 In this manner the two elements are held against accidental or casual displacement and it will be impossible to disconnect the complementary members of the fastener 60 until the spring member is pulled outwardly therefrom.

What I claim is:—

A garment fastener comprising a pair of complementary disks, one of said disks having a centrally located stud having an 65 enlarged spherical head, the other disk being provided with a central opening having communication with a rectangular slot, said opening being sufficiently large to receive the head of said stud, a resilient spring 70 formed on the edge of the central opening at a point opposite the rectangular slot, and a finger angularly disposed on the end of the resilient spring so that same is positioned directly over the rectangular slot and 75 engages the spherical head for holding the stud in the slot when the complementary fastening members are assembled.

In testimony whereof, I have affixed my signature in the presence of two witnesses. 80

ROY H. ANDERSON.
